Design No 599

Fig. 2

Book Case and Stove designed
of Julius Volger

Design for bookcase, stove
Patented Oct. 4, 1853

Dec. 599

Julius Holzer of Philadelphia, Pa.

Assignor to

North, Chase & North of same place.

Letters Patent No. 599. Dated Oct. 14th, 1853.

The schedule referred to in these Letters Patent, and making part of the same.

To all whom it may concern:

Be it known, that I, Julius Holzer, of the City and County of Philadelphia, and State of Pennsylvania, have invented a new design for stoves; and I do hereby declare that the following is a full and exact description thereof, reference being had to the accompanying drawings, which form a part of this specification.

a, b, c, d, e, are panels. In the center of each panel is an Elizabethan shield i, the panels being bordered by a null moulding f. A similar null moulding is used as a border to the bottom plate, fig. 3. l is a foliated club clasped at its center by a ring m. n is a modification of the shield, used for a foot. o, o, o, o, are four apertures in the side plates.

Fig. 1 represents a side plate; fig. 2, a front plate; fig. 3, a section of a bottom plate of a stove to which the above design has been applied.

What I claim as my invention, and desire to secure by Letters Patent, is the use of the ornaments and null mouldings herein described, forming an ornamental design for stoves.

Witnesses,

Stephen Tarrain, }
Wm. P. Bolton.

Julius Holzer.
